UNITED STATES PATENT OFFICE.

JOHN T. GREENWOOD, JR., OF BELOIT, WISCONSIN.

COMPOUND FOR GRAINING WOOD.

SPECIFICATION forming part of Letters Patent No. 260,973, dated July 11, 1882.

Application filed April 20, 1882. (No specimens.)

To all whom it may concern:

Be it known that I, JOHN T. GREENWOOD, Jr., a citizen of the United States, resident of Beloit, in the county of Rock and State of Wisconsin, have invented a new and valuable Improvement in Compounds for Graining Wood; and I do hereby declare that the following is a full, clear, and exact description of the same.

This invention has relation to compounds for graining on wood; and it consists in a mixture of the ingredients hereinafter named, in the proportions set forth.

In preparing this graining compound I take one quart of malt vinegar, two ounces of brown sugar, one-quarter of an ounce of fish-glue, one-half an ounce of alcohol, and four drams of the oil of sassafras, and mix them together.

Mineral paints are used for ground-work,

and when the compound above set forth is used in connection with such paints a body is formed suitable for graining in imitation of oak, maple, black-walnut, or French walnut.

Having described this invention, what I claim, and desire to secure by Letters Patent, is—

The graining compound consisting of malt vinegar, brown sugar, fish-glue, alcohol, and oil of sassafras, mixed together in the proportions substantially as specified.

In testimony that I claim the above I have 30
bereunto subscribed my name in the presence
of two witnesses.

J. T. GREENWOOD, JR.

Witnesses:

P. JOHNSON,
E. P. KING.
